UNITED STATES PATENT OFFICE.

JAMES P. LEE, OF HARTFORD, CONNECTICUT.

CARTRIDGE-CLIP.

SPECIFICATION forming part of Letters Patent No. 653,389, dated July 10, 1900.

Application filed August 8, 1899. Serial No. 726,536. (No model.)

To all whom it may concern:

Be it known that I, JAMES P. LEE, a citizen of the United States of America, and a resident of the city and county of Hartford, in 5 the State of Connecticut, have invented certain new and useful Improvements in Cartridge-Clips, of which the following is a specification.

This invention relates to cartridge-clips or 10 magazine-filers especially adapted for use in connection with that class of small-arms commonly known as "bolt-guns" or "magazine-guns."

An object of the present invention is to furnish a clip of materially-simplified construction and organization embodying a cartridge-locker adapted when in its locking position to bear against the head-faces of every cartridge of and to positively lock a row of superimposed cartridges, and which clip will occupy the least possible space over and above that actually required for the cartridges and which will be light, strong, and serviceable, may be quickly operated to lock the cartridges in place by a simple longitudinal movement of one member thereof, may be automatically operated by a fixture on the gun during the insertion of the clip to release the cartridges, and may be so inexpensively manufactured as to allow the throwing away of said clips without material loss.

A further object of the invention is to produce a cartridge-clip including a substantially-rigid channelled clip-body or holding 35 member and a substantially-rigid cartridge-locking member supported for longitudinal movement and having at opposite ends thereof locking-faces and means effective on the longitudinal movement of either the locker 40 or clip-body, one relatively to the other, for imparting a forward movement to said locker whereby to lock the cartridges.

In the drawings accompanying and forming part of this specification, Figure 1 is a central longitudinal section of a cartridge-clip embodying my present invention in one form thereof, said figure showing a row of superimposed cartridges locked in place in said clip, a portion only of said cartridges being 50 shown. Fig. 2 is a similar view of the clip shown in Fig. 1, showing the cartridges re-

leased and dropping out of the clip. Fig. 3 is a similar view of a slightly-modified form of clip embodying this invention, the cartridges being shown locked in place in the 55 channel of the clip-body or holder and the cartridge-locker proper being shown with resilient actuating projections at opposite ends thereof. Fig. 4 is a plan view of the clip shown in Fig. 1. Fig. 5 is a rear view of the 60 holder or clip-body shown in Fig. 1. Fig. 6 is a front view of the clip illustrated in Fig. 1 without the cartridges. Fig. 7 is a front view of a modified form of clip-body embodying this invention, said figure showing the 65 clip-body furnished with internally-projecting prongs which overlap and hold the cartridge-locker in place in the channel of said body. Figs. 8 and 9 are edge and front views of the cartridge-locker shown in Figs. 1 and 70 2. Fig. 10 is an edge view of the cartridge-locker shown in Fig. 3; and Figs. 11 and 12 are longitudinal sectional views of a portion of the end of the clip-body shown in Fig. 1, showing a modified form of locker in two positions, respectively, said locker being shown 75 with a hook at the end for engaging the clip-body.

Similar characters represent like parts in all the figures of the drawings. 80

The cartridge clip in the preferred construction and organization thereof shown in the accompanying drawings comprises two principal members—to wit, a longitudinally-channelled substantially-rigid clip-body or holding member (designated in a general way by B) and a cartridge-locking member or "locker" (designated in a general way by L) supported for longitudinal and transverse movement with relation to said clip-body. 85 9c

The clip-body B, which will preferably be made of sheet-steel and substantially rigid, is shown having longitudinally-disposed forwardly and inwardly projecting flanges 3 and 3' at opposite side edges, respectively, thereof, 95 which form between them a wide cartridge-head-receiving channel 4, said flanges being disposed at such a distance apart as to permit the flanged or beaded heads 5 of the cartridges C to freely slide within the channel 4, while the inwardly-projecting portions of said flanges 3 and 3' will enter the grooves 5' 100

of said cartridges in the usual manner and as described, for instance, in Letters Patent of the United States, granted to me October 8, 1895, to which reference may be had.

5 The clip-body is shown dished or countersunk longitudinally upon its front or inner face, substantially midway its width, to form a narrow channel 7 to receive the cartridge-locker L, the rear wall of said channel 7 forming a bearing for said locker out of the plane of the head-faces of the cartridges and out of the plane of that portion of the channel 4 against which said head-faces bear.

The clip-body B is shown having at each 5 end thereof a locker-advancing portion or wall 8 and a recess or cartridge-locker-relieving space 9, adjacent to said wall 8, the former being effective when the locker is in its cartridge-holding position for retaining 10 the locking ends of said locker in tight engagement with the heads of the cartridges and at the same time preventing accidental longitudinal movement of said locker, and the latter being effective on a slight longitudinal 15 movement of the locker or clip-body, one relatively to the other, for permitting a backward movement of the locker bodily or of the locking ends of the locker, whereby to release said locker from locked engagement 20 with said cartridges, as will be hereinafter more fully described.

In some instances the clip-body B will be furnished with inwardly-projecting prongs, 25 as 10 and 10', which may be struck out of the metal nearly midway the length of said body and so constructed and disposed as to overlap and engage the front face of the locker, whereby to hold the same with relation to the clip-body, as shown in Fig. 7. Therefore it will 30 be obvious that the invention is not limited to the particular form of clip-body illustrated in any one of the figures of the accompanying drawings, as various modifications thereof are within the purview of this invention.

45 The cartridge-locker L, which constitutes an essential element of the clip, consists, in the preferred form thereof shown in the drawings, of an elongated member constructed of rigid or resilient metal, as desired, and having 50 at or near each end thereof two oppositely-disposed projections 12 and 12', one of which, as 12, extends forward from the front face of said member and constitutes a locking projection or inclined locking-face for engaging the heads of the terminal cartridges 55 of a row of superimposed cartridges for locking the same tightly together, and the other of which, as 12', extends backwardly and constitutes a locker-actuating cam or projection 60 and co-operates with the locker-advancing portion or wall 8 of the clip-body B on a longitudinal movement of said locker or clip-body, one relatively to the other, for imparting a forward cartridge-locking movement of the 65 locker bodily or of the locking ends of said locker.

The cartridge-locker will preferably be rigid from end to end, and the opposing projections 12 and 12' will be so located with relation to each other that when the locker is 70 moved longitudinally of the clip-body into a cartridge-locking position the cam-like projection 12', bearing against the inner face of the wall 8 of the clip-body, will positively prevent a backward cartridge-unlocking movement of said locking projections 12 of said locker, and will also prevent accidental longitudinal movement of said locker relatively to the clip-body.

The locking-faces 12 at opposite ends of 80 the cartridge-locker extend over and under, respectively, the upper and lower faces of the heads of the uppermost and lowermost cartridges of the row of cartridges and tend to force all of the cartridges tightly together, 85 thus positively locking the same together, as will be readily understood.

In Figs. 3 and 10 of the drawings the opposite ends of the elongated locker member, which in these figures is designated by L', 90 are shown bent forward to form the locking projections 12^a and then bent backward and inward to form resilient cam-like projections 12^b, such construction permitting a slight yielding of each actuating-cam face on a longitudinal locking or releasing movement of the locker L' and also compensating for any inaccuracy in construction, which might otherwise result in slight play or looseness.

I do not limit myself to the exact construction of cartridge-locker shown in the drawings, as the same is capable of various modifications within the limit and scope of this invention, so long as the same is constructed and organized to have forward and backward 105 cartridge locking and releasing movements on longitudinal movements of said locker or the clip-body, one relatively to the other.

By reference to Fig. 1 it will be seen that when the cartridges are locked in place in the clip the locking-faces 12 12 of the locker are pressed tightly against the bevel-faces of the flanges of the terminal cartridges of the row by the rear face of the cam-like projections 12' 12' bearing against the inner face of the 115 locker-advancing portion 8 of the clip-body and that the forward face of the body portion of the locker L is, on account of the flexing of the opposite ends of said locker or the lateral movement of said locker bodily, as 120 the case may be, forced tightly against the head-faces of the cartridges, thus preventing accidental movement of said cartridges. When it is desired to release said cartridges from their locked position, it is simply necessary to hold the clip-body member or the locking member, one as against movement longitudinally and move the non-held member longitudinally, so that the cam-like projection 12 will come into register with the recess or relieving-space 9 of the clip-body, when 125 said locking member will be freed from and

will naturally move backward out of locked engagement with the cartridges, one actuating-cam entering a recess 9 and the other extending below the lower end of the clip-body, 5 as shown in Fig. 2, thus releasing the cartridges and permitting the same to move freely out of the clip-body and into the magazine of the gun.

In practice the releasing movement of the 10 cartridge-locker will be automatically effected by a fixture on the magazine of the gun concurrently with the insertion of the clip in the gun-magazine.

A simple and convenient way of releasing 15 the cartridges from locking engagement with the locker and clip-body is to hold the clip-body against longitudinal movement and then push the cartridges toward the lower end of the clip, which will cause the locker to move 20 longitudinally with said cartridges until it comes to the cartridge-unlocking position, (shown in Fig. 2,) when it will be freed from its locked engagement with said cartridges.

In Figs. 11 and 12 the cartridge-locker, 25 which in these figures is designated by L^2 , is shown having a rearwardly-extended hook-like projection 12^c , which not only constitutes the locker-actuating projection or cam, but also constitutes a device for limiting the longitudinal movement of the locker relatively to the clip-body and also prevents displacement of one relatively to the other, said projection being constructed to engage over the edge of the recess 4 in the clip-body on a longitudinal and backward cartridge-unlocking movement of said locker.

It is distinctly to be understood that the invention is not limited to the exact construction and organization of cartridge-clip body 40 and locker illustrated in the accompanying drawings and that various constructions and organizations of said body and locker are within the purview of this invention, so long as means are provided in connection therewith for imparting a forward cartridge-locking movement to the locker on a longitudinal movement of said locker and body, one relatively to the other.

In contradistinction to cartridge-clips of 50 known construction in which resilient lockers are employed and which are normally held in yielding locked engagement with the cartridges by their inherent elasticity, and in which a positive retractive cartridge-unlocking movement is imparted to the cartridge-locker by any means, the cartridge-locker illustrated in the accompanying drawings is not dependent upon its elasticity for holding the cartridges nor for its cartridge- 55 unlocking movement; but, on the contrary, it has a positive advancing cartridge-locking movement imparted to it by the locker-advancing walls 8 of the clip-body coacting with the cam-like projections 12^c on the locker, and 60 the cartridge-engaging ends of the locker are positively held against retractive movement

between the walls 8 and the terminal cartridges of the series when the cartridges are locked in place and cannot be displaced by end thrust on the cartridges. 70

I claim—

1. A cartridge-clip including two co-operative rigid members; and means operative on a longitudinal movement of one member relatively to the other for imparting an advancing cartridge-locking movement to one member. 75

2. A cartridge-clip comprising a clip-body or holding member; a cartridge-locking member; and means for imparting a forward cartridge-engaging movement to both ends of the locking member, simultaneously, on one longitudinal movement of one member relatively to the other, and for effecting the release of both ends of said locking member, simultaneously, on another longitudinal movement of said member. 80

3. A cartridge-clip embodying two substantially-rigid members disposed for longitudinal movement one relatively to the other to 90 lock and release a row of cartridges; and means for advancing both ends of one member to engage the cartridges on one longitudinal movement of the members relatively, and for releasing both ends of said member 95 from engagement with said cartridges on another longitudinal movement of said members.

4. The combination with a clip-body, of a cartridge-locker disposed for longitudinal 100 movement with relation to said body; and means on the body and locker to co-operate and impart to the locker, bodily, a forward cartridge-engaging movement on the longitudinal movement of the body or locker relatively, and to positively hold both ends of 105 said locker against retractive movement when in a cartridge-locking position.

5. A cartridge-clip including a substantially-rigid channelled body or holder; a locker 110 loosely disposed in the channel of said body for bodily movements both longitudinally and transversely of said body; and means on the body and locker to impart a forward cartridge-engaging movement to both ends of 115 said locker on a longitudinal movement of said body or locker one relatively to the other.

6. A cartridge-clip comprising a channelled clip-body having locker advancing and relieving portions at opposite ends; and a locker 120 having cartridge-locking faces at opposite ends on the front face thereof and having locker-actuating projections near opposite ends on the rear face thereof, which latter projections co-operate with the clip-body to 125 impart a forward cartridge-locking movement to opposite ends of said locker simultaneously on a longitudinal movement of the body or locker one relatively to the other.

7. In a cartridge-clip, a cartridge-locker 130 having a locking projection at each end on the front face thereof, and also having a re-

silient actuating cam or projection at each end on the rear face thereof, substantially as and for the purpose described.

8. A cartridge-clip comprising a substantially-rigid channeled clip-body having a locker-advancing wall at the end thereof and also having a recess or relieving-space immediately adjoining said wall; a cartridge-locker having an actuating cam or projection on the rear face near the end thereof coöperating with the locker-advancing wall of the clip-body for normally holding the locker in tight locked engagement with the cartridges and which projection is adapted on a longitudinal movement of said body or locker, one relatively to the other, for entering the recess in said body to release the locker from its locked engagement with said cartridges.

9. In a cartridge-clip a longitudinally-channeled clip-body, in combination with a rigid cartridge-locker loosely disposed in said channel; and means effective on a longitudinal movement of said body or locker, one relatively to the other, for imparting an advancing movement bodily to said locker to throw the same into tight locked engagement with the cartridges and for holding the same against retractive movement until another longitudinal movement of said body or locker, relatively.

10. The combination with a cartridge-clip body, of a non-flexible locker having cartridge-locking projections on the front face at opposite ends and having locker-actuating projections on the rear face at opposite ends,

substantially as described and for the purpose set forth.

11. A cartridge-clip including two coöperative rigid members; means operative on longitudinal movements of one member relatively to the other for effecting forward and backward movements of one member bodily with relation to the other member; and means for limiting the longitudinal movement of one member relatively to the other and for preventing accidental displacement of said members relatively.

12. The combination of a clip-body having a recess near one end thereof, and a rigid cartridge-locker disposed for longitudinal and transverse, bodily, movements with relation to said body and having a forwardly-projecting locking-face and a rearward hook-like actuating projection at one or both ends thereof the latter of which is constructed to impart a forward cartridge-locking movement to the locker on a longitudinal movement of the locker or body, relatively, and is also adapted to engage over the edge of the wall of the recess in said body when said locker is released from said cartridges, whereby to limit the longitudinal movement of the locker and prevent accidental displacement thereof relatively to said body.

Signed by me at Hartford, Connecticut, 65 this 29th day of July, A. D. 1899.

JAMES P. LEE.
